METHOD OF LAPING VALVE PLUGS

George F. Scherer, San Francisco, Calif., assignor to Merco Nordstrom Valve Company, Pittsburgh, Pa., a corporation of Delaware

Application November 12, 1938, Serial No. 239,905

3 Claims. (Cl. 51—281)

The present invention relates to plug valves intended for high temperature service.

It has heretofore been observed that when plug valves, whether lubricated or not, which have been carefully lapped and adjusted to be seated against the pressure carried by the line at ordinary temperatures, are subjected to services carrying fluid at elevated temperatures, the valves frequently become stuck or develop leaks, or both. According to the present invention, I fit the valve member of a valve into its seat at a temperature above normal or room temperature, preferably substantially at the temperature for which the valve is intended to operate. As a result, such valves maintain a tight seal at the elevated temperature at which they are operated, are easy to turn, and, contrary to expectations, do not leak when the temperature is reduced.

Any suitable apparatus may be used for heating the valve, or for maintaining the valve at an elevated temperature during the fitting operation, and the fitting operation may be carried out in any suitable way. For example, in applying the invention to a plug valve, the valve may be submerged in a bath of high boiling mineral oil, molten metal, or a sand bath or other heat transfer medium heated by a gas burner or other suitable source of heat, and lapped at temperatures of about 400° Fahrenheit to 1000° Fahrenheit or at any other temperature above room or normal temperature at which the valves are to be operated in service. The lapping compound may consist of finely divided "Carborundum" or other suitable abrasive suspended in a suitable carrier such as a non-volatile or only slightly volatile mineral oil. After lapping the plug, the valve is removed from the bath, cleaned, assembled and tested at the temperature of the lapping operation. Instead of lapping the valve, the fitting may be accomplished by any other method of grinding or by machining at elevated temperatures.

The invention will be described in detail in connection with the accompanying drawing, in which

Figure 1 shows a preferred apparatus for carrying out the method, and

Figures 2 and 3 show diagrammatically my theory of the distortion due to temperature changes.

Referring to Figure 1, a valve casing 4, shown in longitudinal section, is loosely held in a cradle 5 supported on the bottom of a tank 6 which may be filled with oil 7 above the level of the valve. The tank 6 may be supported on a table

or shelf 8 extending forwardly from an upright post 9, suitably supported. A gas burner 10 or other suitable source of heat is provided beneath the tank 6 for heating the liquid therein. The liquid in the tank may be any suitable hydrocarbon oil boiling above the temperature at which the lapping operation is to be performed, or may consist of diphenyl, a metal having a low melting point, or a bath of sand. The plug 11 of the valve having a port 12 is held loosely by a chuck 15 carried by the spindle 16 so that the plug may freely center itself with respect to the valve seat 17 in the casing.

Spindle 16 is rotatably supported in the sleeve 18 mounted in the outer end of a bracket 20 supported by the upright 9, and the rear side of sleeve 18 is provided with a rack 21 meshing with a gear 22 mounted on a shaft 24 journalled in the bracket 20. If desired, one end of shaft 24 may be square to receive the inner end of a handle 25 carrying a weight 26. The upper end of spindle 16 is journalled in the projecting part 27 of the upright 9 and has a bevel gear 28 resting on the extension, the gear 28 being splined 29 on the upper end of the spindle 16 so that the spindle may be moved axially therethrough while the gear is rotating. Gear 28 is driven by bevel gear 30 on one end of a horizontal shaft 31 journalled in the brackets 32 and 33 and carrying 30 a step pulley 34 which may be driven from any convenient source of power.

During operation, while the plug is rotating, it is periodically lifted and returned to its seat. This is accomplished by a mechanism comprising a cam 36 secured to the shaft 24 co-operating with a cam 37 secured on one end of shaft 39 which is journalled in bracket 20. Shaft 39 carries a gear 41 meshing with a gear 42 secured to a shaft 43 journalled in an arm 44 of extension 40 and a boss 46 at the top. A gear 47 at the top of shaft 43 meshes with a gear 48 carried by shaft 31. Preferably, the gearing ratio is such that plug 11 does not make a complete revolution in the valve seat when it is lifted by the engagement of cams 36 and 37, although if desired, the plug may make slightly more than one revolution before it is lifted. Also, it will be understood that instead of rotating the plug it may be oscillated back and forth and periodically lifted, or the lapping operation may be carried out with any other motion known in the art.

The abrasive compound used for the lapping operation preferably consists of a mixture of a high boiling mineral oil and a fine grade of "Carborundum" abrasive powder, and if desired,

the lapping compound may be thickened by the addition of asphalt or other suitable thickening agents. The actual proportions and type of material used for the lapping operation may be varied in known manner in accordance with the nature of the metal of which the valve is made, and the temperature at which the lapping operation is carried out.

A mineral oil bath may be used for carrying out the lapping operation up to about 600° Fahrenheit, and for higher temperatures the sand bath method may be employed, as most oils are volatile above this temperature. It will also be understood that, if desired, the bath may be made up of molten lead or other solid material having a suitable high boiling point so that it will not be volatilized at the temperature at which the lapping operation is carried out. The lapping operation may be carried out at any desired temperature up to about 1000° Fahrenheit or higher.

I believe that the difficulties heretofore experienced in attempting to operate cold lapped valves at elevated temperatures is due to the unequal expansion of the metal, which results from the fact that the various sections of metal in the valve are not of equal thickness. Thus, referring to Figure 2, if a plug 11 having a port 12 therethrough is heated, the chord 51 forming the walls of the port will expand greater than the wall along the transverse diameter, indicated by the dot and dash line 52, and the edges of the port will form projecting lips. These lips may project about ten thousandths of an inch or more, depending on the temperature, properties of the metal, and relative sizes of the various sections. In other words, the plug will assume a generally elliptical shape between the ends of the port, as indicated by the dot and dash line 53. At the same time the seat 17 will expand unequally, the lips 54 adjacent the passageway expanding less than the rest of the seat and as a result the lips 53 of the plug port will abut against the projecting lips 54 of the valve seat. This theory is supported by actual experience as it frequently happens that when valves which are perfectly lapped at normal temperatures are heated and operated, a slight bump can be felt when the edges of the port pass one another at both extremes of the operating arc. Also, frequently scoring occurs, commencing at the edge of the port and extending inwardly along the casing seat.

It is my theory that in lapping the valve at an elevated temperature, these expanded lips of the

valve port and passage are ground off, thus producing a plug having a circular form at the elevated temperature at which lapping occurs, which has a perfect fit with the seat. It is, of course, apparent that when a valve is so lapped and fitted at a high temperature it will assume a slightly oval shape in cross section at lower temperatures. However, in lubricated valves, the slight oval shape appears to have no disadvantage, as the lubricant has sufficient viscosity at low temperatures to provide an adequate seal for the valve. In such a valve, although the viscosity of the lubricant is reduced at higher temperatures, the closer fit of the plug and seat compensates for the decrease in efficiency of the lubricant film and provides a satisfactory seal.

The temperature at which difficulties in operation will be experienced with cold lapped valves will depend on the nature of the metals in the valve, and on other factors. In general, ordinary carbon steel or alloy steels intended for operation at temperatures at or above 400° Fahrenheit should be hot lapped according to the present invention.

At high temperatures a close fit of the plug to its seat is quite essential because at such temperatures the lubricants employed lose their viscosity and sealing properties, whereas in a valve which has a loose fit at low temperatures it is not difficult to provide lubricant at such temperatures having the proper viscosity to seal the valve and prevent leakage.

While I have illustrated my method applied to a plug valve, it will be understood that the invention may be applied to any other type of valve without departing from the spirit or scope thereof.

What I claim as my invention and desire to secure by Letters Patent is:

1. The method of fitting a valve plug into its seat which comprises lapping the plug in its seat in the presence of an abrasive lapping compound at a temperature above normal by the application of extraneous heat.

2. The method of fitting a valve plug into its seat which comprises lapping the plug in its seat in the presence of an abrasive lapping compound at a temperature of about 400° Fahrenheit or higher.

3. In the manufacture of a plug valve, the method which comprises cutting the plug member and its seat to a substantially circular cross section form at a temperature above normal obtained by the application of extraneous heat.

GEORGE F. SCHERER.
